PNEUMATIC HORN

Cecil S. Kelley, Forest Hills, Pa., assignor to Westinghouse Air Brake Company, Wilmerding, Pa., a corporation of Pennsylvania

Application November 3, 1936, Serial No. 108,924

3 Claims. (Cl. 116—138)

This invention relates to sound producing devices, and more particularly to the type employing a vibratory element.

In designing sound producers of the above type it has heretofore been proposed to employ vibratory elements such as diaphragms or valves, sometimes having biasing means associated therewith, which elements are secured in their operating positions by suitable means and are adapted to vibrate for producing sounds when subjected to differential pressures. Difficulty may be experienced in operation of such sound producers due to breakage of the diaphragms or the biasing springs, and in addition the resistance to movement of the vibratory elements may be such as to render operation of the sound producers by partial vacuum impracticable.

The principal object of my invention is to provide an improved sound producer of rugged and inexpensive construction, which has a freely movable vibratory element operable by a partial vacuum and so arranged as to dispense with springs or other biasing means.

In the accompanying drawing, Fig. 1 is a view, mainly in section, of a sound producing device constructed according to my invention; and Fig. 2 is a plan view of one of the vibratory disk valves shown in Fig. 1.

Referring to the drawing, the sound producing device shown is of the dual type, comprising two similar units arranged side by side and adapted to be operated to produce a double note, although it will be understood that my invention may be embodied in a device consisting of one or any number of units as desired.

As shown in the drawing, the sound producing device comprises a body casing 1, which is adapted to be mounted on a support by any suitable means (not shown), and has formed on one side thereof a pair of tubular boss portions 3 in which are secured the ends of horns 4 and 4'. Mounted in the body casing 1 are similar valve seat members 6, each of which has screw threaded connection in one of a pair of suitable bores formed in the body casing in alignment with the respective horns 4 and 4'.

Each seat member 6 is cylindrical in form and is provided with an end portion 8, which is in sealing engagement with an annular shoulder 9 formed within the body casing adjacent a chamber 10 that is open to atmosphere through the associated horn. The end portion 8 of each seat member 6 has formed thereon an inverted annular seat rib 11 surrounding an aperture 12 which opens into the chamber 10.

A pair of adjustable hollow elements 14 are mounted in and have screw-threaded engagement with the seat members 6, each of said elements having formed on one end thereof an annular seat rib 15, which surrounds a central bore 16 in the element and is adapted to be aligned with the inverted seat rib 11 on the associated seat member 6.

Interposed between the seat ribs 15 and 11 in each unit of the sound producing device is a disk 10 valve 17, which has several circumferentially spaced guide lugs 18 formed thereon and which slidably engages the wall of an annular chamber 19 surrounding the seat ribs 15 and 11 in each of the seat members 6. Each of the chambers 19 is connected to a pipe 24 by way of apertures 21 formed in the respective members 6, annular grooves 22 formed in the body casing 1, and passages 23. The pipe 24 is adapted to be connected, when it is desired to operate the sound producing device, to a suitable partial vacuum source.

The distance between the aligned seat ribs 11 and 15 is greater than the thickness of the valve disks 17, which are adapted to be alternately impinged into seating engagement with said ribs to produce sounds in the manner hereinafter explained. The tonal quality of the sounds produced is determined in part by the distances between the seat ribs, which may be varied as desired by adjustment of the screw-threaded elements 14 within the members 6. Lock nuts 25 are provided on the respective elements 14 and are adapted to be turned into engagement with the outer ends of the seat members 6 for locking the elements 14 in their adjusted positions.

In operation, assuming that the valve disks 17 are initially in seating engagement with the seat ribs 15 as shown in the drawing, when a partial vacuum is created in the pipe 24, air is withdrawn from the chamber 10 and aperture 12 adjacent each valve disk by flow past the seat rib 11 and through the annular chamber 19, apertures 21, groove 22 and passage 23 at such a rate as to effect a rapid reduction in the fluid pressure acting on the right-hand face of each valve disk. The atmospheric pressure of air in each of the bores 16 is then sufficient to move the adjacent valve disk 17 away from the seat rib 15 and into seating engagement with the seat rib 11 associated therewith, thus opening communication between the bores 16 and the chambers 19.

With the valve disks 17 in engagement with the seat ribs 11, the fluid pressure in the chambers 10 and bores 12 is quickly restored to that

of the atmosphere, while the fluid pressure in the bores 16 is reduced by suction of air through the chambers 19, and passages 21, 22 and 23 and pipe 24. The atmospheric pressure acting 5 through apertures 12 on the valve disks 17 is then sufficient to move said valve disks into engagement with the seat ribs 15.

The operation of the valve disks just described is rapidly repeated as long as a partial vacuum 10 is maintained in the pipe 24, and the resultant vibrations of the disks and the surrounding air produce sounds which are amplified in the usual manner by the horns 4.

It will be apparent that the sound producing 15 device comprises relatively few parts and is thus capable of being manufactured at minimum cost, and that the freely movable and unbiased vibratory element provided in the device is adapted to resist possible breakage in operation.

20 While one illustrative embodiment of the invention has been described in detail, it is not my intention to limit its scope to that embodiment or otherwise than by the terms of the appended claims.

25 Having now described my invention, what I claim as new and desire to secure by Letters Patent, is:

1. A sound producing device comprising a body, a seat member removably mounted in said body 30 and having an annular seat rib surrounding an atmospheric opening, a member adjustably mounted in said seat member and carrying an annular seat rib surrounding an atmospheric opening in alignment with and spaced from 35 the first-named seat rib, a chamber surrounding said seat ribs, and a disk valve interposed between and freely movable into and out of seating engagement alternately with said seat members upon the creation of a partial vacuum in said 40 chamber.

2. A sound producing device comprising a body, a seat member removably mounted in said body and having an inverted annular seat rib surrounding an atmospheric opening, an adjustable member having screw-threaded connection in said seat member, an annular seat rib surrounding an atmospheric opening in said adjustable member and adapted to be spaced from and aligned with the first-named seat rib, a chamber surrounding said seat ribs and connected to means for creating a partial vacuum therein, a vibratory disk valve of a thickness less than the distance between said seat ribs and interposed therebetween, said disk valve being operative upon the creation of a partial vacuum in said chamber to engage said seat ribs alternately for opening and closing communication between said chamber and the atmosphere through each of said atmospheric openings in succession, and means for amplifying the sound thereby produced by vibration of 20 said disk valve.

3. A sound producing device comprising a body, a seat member removably mounted in said body and having an inverted annular seat rib surrounding an atmospheric opening, an adjustable member having screw-threaded connection in said seat member, an annular seat rib surrounding an atmospheric opening in said adjustable member and adapted to be spaced from and aligned with the first-named seat rib, a chamber surrounding said seat ribs and connected to means for creating a partial vacuum therein, and a disk valve interposed between said seat ribs and having a plurality of spaced lugs on the periphery thereof in sliding engagement with the wall of 30 said chamber, said disk valve being freely movable into and out of seating engagement with said seat ribs in succession upon the creation of a 35 partial vacuum in said chamber.
